UNITED STATES PATENT OFFICE.

CHARLES THOMAS McGREGOR, OF DENISON, TEXAS.

TRAIN SIGNALING AND STOPPING DEVICE.

1,356,299.

Specification of Letters Patent.

Patented Oct. 19, 1920.

Application filed May 3, 1918. Serial No. 232,266.

To all whom it may concern:

Be it known that I, CHARLES T. McGREGOR, a citizen of the United States, residing at Denison, in the county of Grayson and State of Texas, have invented certain new and useful Improvements in Train Signaling and Stopping Devices; and I do hereby declare the following to be a full, clear, and exact description of the invention, such 10 as will enable others skilled in the art to which it appertains to make and use the same.

This invention relates to improvements in train signaling and stopping devices, and its 15 primary object is the provision of an electrically operated device of this character, which shall be simple, durable and efficient, and which may be manufactured, sold, and erected at a comparatively low cost.

20 With the foregoing and other objects in view this invention consists in such novel features of construction, combination and arrangement of parts as will be hereinafter more fully described, illustrated in the accompanying drawings and claimed.

25 In describing the invention in detail, reference will be had to the accompanying drawings wherein like characters designate like and corresponding parts throughout the several views and in which:

Figure 1 is a vertical sectional view of a train signaling and stopping device constructed in accordance with my invention.

Fig. 2 is a similar view on an enlarged scale.

Fig. 3 is a horizontal section taken on the horizontal plane indicated by the line 3—3 of Fig. 1.

Fig. 4 is a vertical section through the obstacle operated by the signaling mechanism and placed for engagement with the train carried signaling means.

Fig. 5 is a fragmentary sectional view illustrating one of the catch levers for holding the lever which is connected to the semaphore arm, in various adjusted positions.

Fig. 6 is a fragmentary view of an engine illustrating the signaling means carried thereby.

Fig. 7 is a detail perspective of a part of the signaling means carried by the engine which is engaged by the track obstacle.

Fig. 8 is a detail view of the air-line bleed valve operated by the train carried signaling means to stop the train after the same passes a signal set at "danger."

Fig. 9 is a detail view on an enlarged scale of the semaphore arm controlling and actuating lever, illustrating the circuits of the motor and the switch controlling circuits.

Fig. 10 is a horizontal section through a portion of the lever, illustrating the connection between the lever and the rod by which the lever is connected to the semaphore arm, and

Fig. 11 is a detail view illustrating the latch employed to secure the upper switch lever carried by the locomotive in actuated position.

The signaling mechanism comprises a casing 3 through which a vertical rod 4 extends. The rod 4 projects above the casing 3 and is inclosed in a suitable casing or pipe 5 which carries slide bearings 6 for the rod 75 4. The upper end of the rod 4 is connected as shown at 7 to the arm 8 which is formed upon the semaphore arm 9 and projects oppositely from the pivot 10 thereof to the blade or exhibited arm of the semaphore so 80 that the semaphore 9 and the rod 4 will move in unison. The semaphore 9 is pivotally supported by the pin 10 which pin is in turn carried by the casing 5. The casing or pipe 5 has an arcuate plate 11 supported 85 at its upper end which is provided with transparent panels 12 of different colors, namely the colors commonly employed in railway signaling, such as green for safety, yellow or orange for caution and red for 90 danger. These panels 12 are positioned so that they will align with the semaphore 9 when it is in the respective position indicating safety, caution, and danger.

The rod 4 projects downwardly within 95 the casing 3, being slidably supported by suitable slide bearings 14 and it has rack teeth 15 carried by its lower end. A pipe 16 extends into the ground beneath the casing 3 and the lower end of the rod 4 extends 100 downwardly into the pipe.

A rod 17, is rotably supported by the casing 3 and it has a gear 18 mounted thereon which meshes with the rack teeth 15. The shaft or rod 17 extends through a pipe 19 105 which forms a protection therefor and into a vertically positioned casing 20. The casing 20 is positioned alongside of the rails of the railway track and it has a rod 21 slidably supported therein. A head 22 is 110 formed upon the upper end of the rod 21 and acts as an obstacle along the track to

be engaged by the train carried signaling means. The rod 21 has rack teeth 23 formed thereon which mesh with a gear 24 carried by the rod 17 so that through the 5 medium of the rack teeth 23, the gear 24, the rod 17, the gear 18 and the rack teeth 15 the rods 4 and 21 will be moved in unison for regulating the upwardly projecting position of the head 22 of the rod 10 21 in accordance with the position of the semaphore 9. For instance when the semaphore 9 is positioned at "caution," the rod 21 will be projected above the upper end of the casing 20, a sufficient distance to 15 strike the resilient lever 25 of the train signaling means. The lever 25 is connected to a vertical pin 26 which is in turn supported by a plate 27. The plate 27 is carried by a depending pipe or rod 28 which may be 20 attached to the tender of the engine or in any convenient place. A pair of contacts, 29 and 30 are carried by the plate 27, which plate is preferably of insulating material and these contacts are connected through 25 the medium of wires 31 and 32 with a signal light 33 which is positioned in the cab of the engine. When the rod 21 is moved into a "caution" position, it will strike the resilient lever 25 and set up a vibratory 30 motion of this lever which will cause the lever to intermittently engage the contacts 29 and 30 and consequently intermittently close a circuit through the light 33, causing a flickering or intermittent lighting of 35 the light so as to acquaint the engineer of the fact that he has passed a block signal set at "caution." When the semaphore arm 9 is set at danger, the arm 21 will be projected a greater distance above the upper 40 end of the casing 20, than it is projected when the semaphore arm is set at "caution" and it will therefore strike the lever 34 which is pivotally supported by a suitable pin 35 carried by a plate 36. The plate 45 36 is also carried by the post 28. The lever 34 travels in a guide 37 which is carried by the plate 36. The guide 37 has contacts 38 and 39 connected thereto with which the lever 34 engages, when it is operated by the 50 head 22 of the arm 21. When the lever 34 is forced into engagement with the contacts 38 and 39, it is held in such position against the tension of the spring 46^a of the valve 46 by a spring latch 34^a as shown in Fig. 11, 55 a circuit will be closed through the light 33, by the wires 40 and 41 and as the lever 34 is not resiliently mounted, a continuous burning light will be provided until the lever 34 is moved out of engagement with 60 the contacts 38 and 39, thus acquainting the engineer with the fact that he has passed a signal set at danger. The end of the lever 34 which projects oppositely from the pivot 35 to the guide 37 is angled as shown at 42

and it is positioned for engagement with the yieldably mounted head 43 of a bleed valve structure 44. The bleed valve structure 44 is connected to the air-line 45 of the train, so that when the angled end 42 strikes the head 43 it will unseat the valve cone 46, 70 and consequently open the bleed valve 44, to bleed the air-line 45 and apply the brake, to stop the train.

A lever 55 is pivotally supported as shown at 56 within the casing 3 and the rod 4 is connected to said lever. As shown in Fig. 10, the rod 4 passes through an elongated opening 4^a formed in and extending longitudinally of the lever 55. The rod 4 carries pins 4^b which work in slots 4^c formed in the side walls of the opening 4^a, so as to permit of movement of the rod vertically with the pivotal movement of the lever 55. The weight of the semaphore 9 is such, that it will move the lever 55 with the movement of the semaphore, and under the weight of the semaphore arm 9 except when the lever is restricted by the upper and lower catch structures 58 and 59, respectively.

The lower catch structure 59 is adapted to hold the semaphore arm 9 in vertical or safety position, and the upper catch structure 58 is adapted to hold a semaphore arm 9 in an upwardly inclined or caution position. Each catch structure comprises a substantially vertical arm 60 which is pivoted between its ends to a horizontal bracket 61. A right angularly extending head 62 is formed upon the upper end of the pivoted arm 60 and it has a latch 63 connected to one of its ends. The latch 63 is adapted to engage the upper side of the lever 55 and hold it against upward movement and the semaphore arm 9 against downward movement. A rod 63' is pivotally connected to the other end of the head 62, and it is slidably mounted in a guide 64. A contractile spring 65 is connected at one end to the casing 3 and at its other end to the arm 60, and it is adapted to withdraw the latch 63 out of the path of the lever 55, when the arm 60 is released. The arm 60 is provided at its lower end with an armature 66, and a pair of electromagnets 67 are located adjacent the armature 66. When the electromagnets 67 are energized, the latch 63 is held in active or lever engaging position, and when the electromagnets are deenergized the spring 65 holds the latch 63 in inactive or lever releasing position.

A switch 60^a, which is under the control of the upper catch structure 58, comprises a pair of relatively spaced contacts 61^a interposed in a wire 71^a which, together with a wire 71, leads from a track circuit, not shown, to the electromagnets 67 of the lower catch structure 59. Wires 70 and 70^a lead

from the track circuit to the magnets 67 of the upper catch structure 58. When the magnets 67 of the upper catch structure 58 are energized, the switch 60^a is closed, and 5 when those magnets are deenergized the switch is opened. It will thus be seen that the circuit including the magnets 67 of the lower catch structure 59 is closed when the magnets of the upper catch structure 58 are 10 energized and broken when these magnets are deenergized.

In practice, a signaling and train stopping mechanism is located at the entrance to each block of a railway track and the 15 electromagnets of the catch structures are connected by the wires 70, 70^a, 71 and 71^a in a track circuit which will under normal conditions maintain the electromagnets energized, and which will permit the magnets to be short circuited by a train. The 20 semaphore arm 9 is normally held in a vertical or safety position by the latch 63 of the lower catch structure 59. When the electromagnets of this catch structure are short circuited by a train, the spring 65 pulls the 25 latch 63 out of engagement with the lever 55. This frees the lever and the semaphore arm 9, and the semaphore arm moves downwardly under the influence of its own 30 weight and the lever 55 moves upwardly under the influence of the semaphore arm. The movements of the semaphore arm 9 and the lever 55 are arrested by the latch 63 of the upper catch structure 58 when the semaphore arm 9 reaches an upwardly inclined 35 or caution position. The short circuiting of the electromagnets 67 of the upper catch structure 58 by a train, permits the latch 63 of this catch structure to be moved out 40 of engagement with the lever 55 by the spring 65. When the lever 55 is released by this catch structure, the semaphore arm 9 moves downwardly under the influence of its own weight from its caution position to 45 its horizontal or danger position. The downward movement of the semaphore arm 9 to this position will move the lever 55 upwardly, and its downward movement is arrested when it reaches danger position by 50 a stop 89 located in the path of the lever 55.

The semaphore arm is adapted to be returned from danger position to caution position, or from danger position to safety position, or from caution position to safety 55 position, by an electric motor 82 which is fixed to the upper side of the lever 55. A sprocket chain 85 passes about a sprocket wheel on the armature shaft of the motor 82 and about the sprocket wheel on a stub 60 shaft 84 which is journaled upon the upper side of the lever 55 in advance of the motor. A pinion 86 is fixed to the stub shaft 84 and meshes with the teeth 87 of a curved rack 88 which is suspended from the upper side 65 of the casing 3 by an arm 88^a. The arma-

ture shaft of the motor 82^a is also provided with a balance wheel 90. The stop 89 which is adapted to arrest the downward movement of the semaphore 9 when that arm reaches its danger position, is secured 70 to the upper end of the rack 88.

The motor 82^a is connected to the circuit of the upper catch structure in shunt with the electromagnets 67 of such catch structure by wires 80 and 81, and to the circuit 75 of the lower catch structure in shunt with the electromagnets 67 of such lower catch structure by wires 90 and 91.

The wire 80 is connected to a post 80^a which is carried by the base of the motor 82 and which is electrically connected to one of the brushes of the motor. The wire 81 is connected to a contact plate 83 which is carried by the arm 83^a and which is adapted to be engaged by a contact block 84^a. The contact block 84 is carried by the lever 55 and is connected by a wire 84^a to a post 80^b which is carried by the base of the motor 82 and which is electrically connected to the other brush of the motor. The wire 90 is connected to one brush of the motor through the medium of the wire 80 and the post 80^a. The wire 91 is connected to a contact plate 92 which is carried by the arm 92^a and which is adapted to be engaged 95 by a contact block 92^b. The block 92^b is carried by the lever 55, and it is connected to the other brush of the motor by a wire 92^c, the wire 84^a, and post 80^b. When the semaphore arm 9 is in danger position, the contact block 84^a is in engagement with the contact strip 83. As the motor 82 is now in the circuit which includes the electromagnets 67 of the upper catch structure 58, the energization of these electromagnets will 100 also result in the energization of the motor. When the motor is energized, it will, through the medium of the pinion 86 and rack 88, move the lever 55 downwardly in the direction of a position where it will be 105 engaged by the latch 63 of the upper catch structure 58 and move the semaphore arm 9 upwardly in the direction of its caution position. Just before the lever 55 and semaphore 110 arm 9 reach the positions mentioned, the motor circuit will be broken by the contact block 84^a passing out of engagement with the contact strip 83, and the lever and semaphore arm will be moved into the positions mentioned by reason of their inertia 115 and the inertia of the parts associated therewith. When the latch 63 of the upper catch structure 58 engages the lever 55, the semaphore arm 9 will be held in caution position, and the contact block 92^b will be 120 in engagement with the contact strip 92. The motor 82 is now in the circuit which includes the electromagnets 67 of the lower catch structure 59, and when these electromagnets are energized, the motor is also en- 125 130

ergized. This energization of the motor will, through the medium of the pinion 86 and rack 88, move the lever 55 downwardly to a position to be engaged by the latch 63 of the lower catch structure 59 and move the semaphore arm 9 upwardly in the direction of its clear position. Just before the lever 55 and semaphore 9 reach the positions stated, the motor circuit is broken by 10 the contact block 92^b passing out of engagement with the contact strip 92, and the lever and semaphore arm are moved into the position stated by reason of their inertia and the inertia of the parts associated therewith.

15 When the lever 55 is engaged by the latch 63 of the lower catch structure 59, the semaphore arm 9 will be held in clear position.

The semaphore 9 may have two incandescent lights 93 carried thereby which may 20 be connected to the storage batteries 50, along the track by suitable conducting wires 94 so that the lights 93 will be burning at all times.

As previously stated, the movement of 25 the lever 55 will move the rod 4, which will in turn move the semaphore 9 under forced movement of the lever 55 by the motor 82, or the rod 4 will be moved by the movement of the semaphore 9 under its own weight so 30 that all movement of the rod 4 will be transmitted to the vertical rod 21, for operating the engine carried mechanism synchronously with the operation of the semaphore.

35 From the foregoing description taken in connection with the accompanying drawings the advantages of construction and the method of operation of the improved automatic train stop will be readily apparent to 40 those skilled in the art to which this invention appertains and, while in the foregoing description, the principle of the operation of this invention has been described together with various features of construction, it is to be understood that certain minor 45 features of construction, combination and arrangement of parts may be altered to suit practical conditions provided such alterations are comprehended within the scope of 50 what is claimed.

What is claimed is:

1. A train signaling device comprising a semaphore arm adapted to move from safety to caution and from caution to danger 55 and from safety to danger by gravity, a pivoted lever connected to the semaphore arm and adapted to be actuated by the semaphore arm during its movements into the positions indicated, electrically operated 60 latches arranged in the path of said lever to control the movement of the semaphore arm into the positions stated, and electrically operated means coöperating with said lever to move the semaphore arm in the 65 reverse direction.

2. A train signaling device comprising a semaphore arm adapted to move from safety to caution and from caution to danger and from safety to danger by gravity, a pivoted lever connected to the semaphore arm and 70 adapted to be actuated thereby during its movements into the positions stated, latches arranged in the path of said lever to control the movements of the semaphore arm into the positions stated, normally energized 75 electro-magnets adapted to hold said latches in active position, and electrically operated means coöperating with said lever to move the semaphore arm in a reverse direction.

3. A train signaling device comprising a 80 semaphore arm adapted to move from safety to caution and from caution to danger and from safety to danger by gravity, a pivoted lever connected to the semaphore arm and adapted to be actuated thereby during its 85 movements into the positions stated, pivoted latches arranged in the path of the lever, springs adapted to normally hold said latches in inactive position, electro-magnets adapted when energized to hold said latches 90 in active position and electrically operated means associated with the lever for moving the semaphore arm in a reverse direction.

4. A train signaling device comprising a 95 semaphore arm adapted to move from safety to caution and from caution to danger and from safety to danger by gravity, a pivoted lever connected to the semaphore arm and adapted to be actuated thereby during its 100 movements into the positions stated, a pair of pivoted latches arranged in vertically spaced relation, electro-magnets adapted when energized to hold said latches in lever 105 engaging position, electrically operated means adapted to move the lever for moving the semaphore arm in the reverse direction, and means connecting the first named means to the circuit of the electro-magnet of each latch so that said first named means will be 110 energized on the energization of the electro-magnet of either latch.

5. A train signaling device comprising a 115 semaphore arm adapted to move from safety to caution and from caution to danger and from safety to danger by gravity, a pivoted lever connected to the semaphore arm and adapted to be actuated by the semaphore arm during its movements into the positions stated, a pair of pivoted latches arranged in relatively spaced relation, an electro-magnet for each latch 120 adapted when energized to hold the latch in active position, a switch in the circuit of one of said solenoids under the control of the latch actuated by the other solenoid, electric means associated with the lever for moving the semaphore arm in a reverse direction, and means connecting said first named means in circuit with the electro-magnet of each latch so that when either 125 130

electro-magnet is energized, said first named means will be energized.

6. A train signaling and stopping device comprising in combination with a semaphore arm actuated obstacle, a pair of switch levers arranged in vertically spaced relation upon a locomotive, and a lamp circuit under the control of said switch levers, one of these switch levers being adapted to 10 be actuated by the obstacle when the semaphore arm is in caution position, and the other of said switch levers being adapted to be actuated by the obstacle when the semaphore arm is in danger position.
- 15 7. A train signaling apparatus comprising a gravity actuated semaphore arm, a rod connected to the semaphore arm, a pivoted lever connected to the rod and adapted to be actuated by and during the movement 20 of the semaphore arm from its safety to its caution position and from its caution to its danger position and from its safety to its danger position, a magnetic latch adapted when energized to coöperate with the lever 25 to hold the semaphore arm in safety position, a second magnetic latch adapted when energized to coöperate with the lever when the latter is released by the deënergization of the first latch to prevent the semaphore 30 arm from moving below its caution position, a stop adapted to prevent the semaphore arm from moving below its danger position when the lever is released by and as the result 35 the deënergization of the second latch and when it is released by and as the result of the deënergization of both latches, and electric means coöperating with the lever for moving the semaphore arm in the 40 reverse direction.

- 40 8. A train signaling apparatus comprising a gravity actuated semaphore arm, a rod connected to the semaphore arm, a pivoted lever connected to the rod and adapted to be actuated by and during the movement 45 of the semaphore arm from its safety to its caution position and from its caution to its danger position and from its safety to its danger position, a magnetic latch adapted when energized to coöperate with the lever to 50 hold the semaphore arm in safety position, a second magnetic latch adapted when energized to coöperate with the lever when the latter is released by and as the result of the deënergization of the first latch to prevent the 55 semaphore arm from moving below its caution position, a stop adapted to prevent the semaphore arm from moving below its danger position when the lever is released by and as the result of the deënergization of

the second latch or both latches, electric 60 means coöperating with the lever to move the semaphore arm in the reverse direction having circuits connected respectively to the circuits of the magnetic latches, and a switch in the circuits of said electric means under 65 the control of said lever.

9. A train signaling apparatus comprising a gravity actuated semaphore arm, a rod connected to the semaphore arm, a pivoted lever connected to the rod and adapted to be actuated by and during the movement 70 of the semaphore arm from its safety to its caution position and from its caution to its danger position and from its safety to its danger position, a magnetic latch adapted 75 when energized to coöperate with the lever to hold the semaphore arm in safety position, a second magnetic latch adapted when energized to coöperate with the lever when the latter is released by and as the result of 80 the deënergization of the first latch to prevent the semaphore arm from moving below its caution position, a stop adapted to prevent the semaphore arm from moving below 85 its danger position when the lever is released by and as the result of the deënergization of the second latch or by and as the result of the deënergization of both latches, a rack bar located adjacent the lever, 90 a pinion journaled on the lever and meshing with the rack bar, an electric motor mounted upon the lever and adapted when energized to rotate the pinion and having circuits connected respectively to the circuits 95 of the magnetic latches, and switches in the motor circuits under the control of said lever.

10. A train signaling and stopping device comprising in combination with a semaphore arm actuated obstacle, a pair of switch 100 levers arranged in vertically spaced relation upon a locomotive, a lamp circuit under the control of said switch levers, a train pipe bleeding valve under the control of the upper switch lever, the lower switch 105 lever being adapted to be actuated by the obstacle when the semaphore arm is in caution position, and the upper switch lever being adapted to be actuated by the obstacle when the semaphore arm is in danger position.

In testimony whereof I affix my signature in presence of two witnesses.

CHAS. THOMAS McGREGOR.
